UNITED STATES PATENT OFFICE

SCOTT H. LILLY AND GEORGE E. LILLY, OF TOLEDO, OHIO, ASSIGNEES, BY MESNE ASSIGNMENTS, TO ST. REGIS PAPER COMPANY, OF NEW YORK, N. Y., A CORPORATION OF NEW YORK

BAG CLOSURE AND METHOD OF MAKING THE SAME

Application filed May 10, 1928. Serial No. 276,593.

This invention relates to a bag closure and method of making the same, and more particularly to a bag closure employing a metal clip or clips to secure the bag closure. One feature of the invention is the corrugation of the clips along the line where they are bent to prevent the straightening out of the clips after they have been applied to the bag. Details of the invention will appear as the description proceeds.

In the accompanying drawings forming a part of this specification, Figure 1 is a view of a top portion of a bag having the top of its walls bent outward to form flanges; Fig. 2 is a view of a top of a bag looking from the right of Fig. 1; Fig. 3 is a view similar to Fig. 1 showing a metallic closing band in place on the top of the bag; Fig. 4 is a view of Fig. 3 looking from the right, and Fig. 5 is a slight modification of Fig. 4; Fig. 6 is a view of the end of a bag having the metal clip bent into closing position thereon; Fig. 7 is a view of Fig. 6 looking at the right side thereof; Fig. 8 is a diagrammatic plan view of the end of the bag during corrugation; Fig. 9 is a side view of the end of a bag after the closing band has been applied and corrugated; Fig. 10 is a diagrammatic side elevation illustrating the application of a tape carrying metal clips to the tops of bags; Fig. 11 is a partial plan view of Fig. 10; Figs. 12 and 13 are enlarged details of portions of Fig. 11; Fig. 13^a is an enlarged detail plan of a portion of the end of a closed bag; Figs. 14, 15 and 16 are diagrammatic sections illustrating successive steps in the application of the tape to a bag; Fig. 17 is a detail plan of a portion of the tape; Fig. 18 is a diagrammatic side elevation showing a modification of the use of a tape carrying metal clips; Figs. 19 is a diagrammatic side elevation of the conclusion of the process shown in Fig. 18; Figs. 20 and 21 are plan views of the construction shown in Figs. 18 and 19, respectively; Figs. 22 to 32, inclusive, are sections of the construction shown in Figs. 18 to 21, showing the successive steps of the manipulation of the tape and clips and indicating diagrammatically apparatus for performing such manipulation.

In Figs. 1 to 8, there is shown the application of a metal band to the end of a bag for closing the same. A bag 10 is shown having the ends of its walls spread apart to form flanges 11. A metal strip 12 wider than the flanges 11 may be slipped over these flanges, there being flanges 13 at each side of band 12 turned downward and inward so as to enclose the edges of flanges 11. This band 12 may be applied with the body portion thereof straight, as shown in Fig. 4, but preferably, it is bent, as shown in Fig. 5. When thus bent, as shown in Fig. 5, the completion of the application may be accomplished very simply by pressing together the two sides of the band, whereby they are bent inward and downward and together, as shown in Figs. 6 and 7. In Fig. 7, the thickness of the parts is exaggerated for purposes of illustration. The band 12 is shown to be bent along lines 15 and 16 leaving a comparatively flat top. Whether this would be true in the actual construction or not would depend upon the thickness of the walls of the bag, the thickness and stiffness of the metal, the manner of application, etc.

After the band is bent into the desired position over the end of the bag, it is run between rollers 17 and 18 having teeth 19 and 20. The rollers are mounted upon shafts 21 and 22 which are pressed firmly towards each other by any suitable means, not shown. The result of this operation is to produce corrugations 23 in the band 12. These corrugations are continued to the top of the band so that the top forms a wavy line and the force necessary to spread apart the lower edges of the band is thereby materially increased.

In the construction shown in Figs. 10 to 17, a series of bags 24 are carried on a conveyor 25. A reel 26 of tape is employed. In the construction shown, there is attached a series of metal clips 28. This tape is first run over a pasting roll 29 running in a suitable paste tank 30. Preferably, the edge of the paste roll is slightly convex and a grooved roller 31 is employed to press the tape down upon roller 29 so as to curve it into the shape shown in Fig. 14. The convex shape of the paste roller is advantageous for two reasons,

because it enables the initial bending of the tape, as shown in Fig. 14, and also because it picks up the paste on its central portion and applies it to the tape and the pressure spreads this paste towards the sides of the tape. It is desirable to have the paste thoroughly applied to the central portion of the tape and not to have it too thick at the edges, because the spreading of the paste beyond the edges of the tape is undesirable.

After the tape passes from the pasting roller, it is led downward onto the top of a bag 24 passing thereunder on the conveyor 25. Blocks 32 are provided at the sides of the top of the bag and cooperate with rollers 33 and 34 to bend downward the edges of the tape and the ends of clips 28. Beyond blocks 32, rollers 35 are provided on opposite sides of the path of the tape and are adapted to bring the sides of the tape to final bent position against the walls of the bag. Thereafter, the tape and bag walls are run between corrugated rollers 36 which have corrugating teeth so spaced that each clip will be bent transversely as indicated in Fig. 13^a. The size of the teeth is such that there is a complete bend in each clip and, therefore, the resistance to the spreading apart of the ends of the clip is materially increased.

Figs. 18 to 32, inclusive, illustrate diagrammatically the application of a slightly different style of tape and clip to a series of bags. A tape reel 40 is provided from which there is led a tape 41 carrying a series of clips 42 which extend to a considerable distance from one side of the tape. The tape is led over a support 43 against which it is held by a series of rollers 45, 46 and 47. While the tape and clips are thus held upon support 42, the ends of the clips are bent successively by rollers 48, 49 and 50 until they are formed into hooks. Thereafter, the tape is run over a paste applying roller 51, rolling in a paste tank 44. The tape is held in place upon the paste roller by a roller 52.

A bracket 53 rising from paste tank 44 (see Fig. 25) supports a guide 54 upon which the hook ends 55 of successive clips are threaded as they pass the paste roller. The end of supporting rod 55 is bent downward to guide the clips onto the top 56 of a bag 57 which is carried beneath the tape by any suitable means, such as the conveyor indicated in Fig. 10, if desired.

The ends of the clips attached to the tape fall down with the tape against the side of the bag, where they are held by a roller 59, while a roller 60 insures their movement down onto the top of the bag. A roller 61 opposite roller 59 presses against the ends of hooks 55 and bends them firmly against the top of the walls of the bag. Thereafter, the tape and bag walls are moved past a roller 62 and the top ends of the clips are bent over

by a roller 63 against a roller 64 opposite roller 62, in the manner shown in Fig. 29.

In the construction shown, the top 66 of another bag ahead of bag 57 is at the same time opposite a block 65, against which it is pressed by a roller 67, while a roller 68 completes the bending of the tops of the clips to right angles from their initial position. The end of block 65 is beveled, as shown at 69 in Fig. 31, and while the tape and bag walls are held against this end of block 65 by a roller 70, another roller 71 bends the ends of the clips down to the angle in which they are shown in Fig. 31. Thereafter, the tape and clips are run between rollers 72 and 73, which complete the bending of the clips into the shape in which they are shown in Fig. 32.

At the same time the top of another bag 74, in advance of bag 66 and having the tape and clips applied thereto, is passing between corrugating rollers 75 and 76, which corrugate the bag walls and clips in a manner similar to that shown in Fig. 13^a.

It will be seen from the above that in each of the forms shown, metal strips or clips are applied to the end of the bag and used to prevent the opening of the end of the bag. In each instance, the metal is corrugated along the line where it is bent after the bending has been performed. These corrugations along the line of bending greatly increase the resistance of the metal to spreading apart and straightening along the bent line. This corrugation of the metal along the line where it is bent in order to prevent its straightening is one of the principal objects of the invention, and other ways of carrying it out, besides the several forms shown, might be employed without departing from this phase of the invention.

Another important feature of the invention is the method of applying a series of clips to a bag by attaching them to a continuous member and using this continuous member to aid in positioning them with respect to a bag.

While various modifications have been described, it will be readily understood that further modifications may be made within the scope of the appended claims.

What we claim is:

1. The method of closing a bag which comprises attaching a series of metal clips to a connecting member, applying the connecting member and its attached clips to the walls of the bag where a closure is to be formed, and bending the clips to hold the walls of the bag in the desired closed position.

2. The method of closing a bag which comprises attaching a series of metal clips to a connecting member, applying the connecting member and its attached clips to the walls of the bag where a closure is to be formed, bending the clips to hold the walls of the bag in the desired closed position.

bag in the desired closed position, and thereafter corrugating the clips along their line of bending, thereby increasing their resistance to straightening along said line.

5 3. The method of closing a bag which comprises attaching a series of metal clips to a connecting member, applying the connecting member and its attached clips progressively to the walls of the bag where a
10 closure is to be formed, and bending the clips to hold the walls of the bag in the desired closed position.

15 4. The method of closing a bag which comprises applying a series of metal clips transversely of a continuous connecting member, adhering the connecting member across the portion of the bag to be closed, bending the clips to hold the walls of the bag in closed position and thereafter corrugating the clips
20 along the line of bending and thereby increasing their resistance to straightening along said line.

In testimony whereof, we have hereunto signed our names to this specification.

25 SCOTT H. LILLY.
GEORGE E. LILLY.
